United States Patent Office

Des. 225,131
Patented Nov. 14, 1972

225,131

HEAD BAND

Melvin V. Zakarin, 23 Ogden Lane,
Englishtown, N.J. 07726

Filed May 20, 1970, Ser. No. 23,063

Term of patent 3½ years

Int. Cl. D2—03

U.S. Cl. D86—10

Fig. 1.

Fig. 2.

FIG. 1 is a front isometric view of a head band showing my new design, the decorative motif being continuous to the back as indicated; and

FIG. 2 is a rear elevational view of a second embodiment of the design of FIG. 1, the decorative motif of FIG. 2 being continuous around the front and as indicated.

I claim:

The ornamental design for a head band, substantially as shown and described.
